LADY'S HANDBAG

Paul Brown, New Rochelle, N. Y., assignor to Paul Brown-Greher, Inc., New York, N. Y., a corporation of New York

Application February 2, 1953, Serial No. 23,399

Term of patent 3½ years

(Cl. D87—3)

To all whom it may concern:

Be it known that I, Paul Brown, a citizen of the United States and a resident of the city of New Rochelle, county of Westchester, and State of New York, have invented a new, original, and ornamental Design for a Lady's Handbag, of which the following is a specification, reference being had to the accompanying drawing, forming a part thereof, in which:

Fig. 1 is a top plan view of a lady's handbag, embodying my design;

Fig. 2 is a front view thereof;

Fig. 3 is a side view; and

Fig. 4 is a plan view, partly open.

The dominant feature of my novel lady's handbag resides in the appearance of the articulated sliding closure thereof.

I claim:

The ornamental design for a lady's handbag, as shown and described.

PAUL BROWN.
